UNITED STATES PATENT OFFICE.

TRAUGOTT KERNCHEN, OF RENDSEBURG, GERMANY.

VENTILATOR FOR BUILDINGS AND VESSELS.

1,033,805.

Specification of Letters Patent. Patented July 30, 1912.

Application filed February 4, 1911. Serial No. 808,660.

To all whom it may concern:

Be it known that I, TRAUGOTT KERNCHEN, a subject of the German Emperor, and a resident of Rendsburg, Holstein, Germany, have invented new and useful Improvements in Ventilators for Buildings and Vessels, of which the following is a specification.

The present invention relates to a ventilator for buildings of all kinds and ships and cars of all kinds adapted to prevent the entrance of rain water, snow and sun rays into the interior of the building or vessel. The advantage is attained by the employment of caps which are arranged around the principal eduction pipe which is provided with inwardly bent holes or excavations.

The accompanying drawing represents in Figure 1 a form of construction of the invention in a side view partly in section and Fig. 2 shows a horizontal cross-section on line A—B Fig. 1 with a perspective view of the lower part.

The principal eduction pipe *a* which can be provided on the outside of the lower end with a flange or footplate *b*, which serves for fixing on the roof, has in its interior a ring-shaped indentation *c* which serves for collecting the water entering the ventilation or serves for collecting the water caused by condensation of moisture and for freezing the same by means of a small opening which is located above the said foot-plate *b*. The upper end of the pipe *a* is provided with conical holes tapering toward the top or bottom or channels *d* while these excavations

are covered by caps *f* which toward the lower end of the pipe are conically extended and which project above the excavations. 40 These caps *f* are again covered by a conical shield *g* which is for the purpose of getting other indentations for the air draft. This conical shield *g* reaches above the eduction pipe *a* and also above the caps *f* and is extended conically on the upper end *h*. Above this cover opening *h* there is at a certain distance a double conical-shaped cap *i* while a broad ring runs around the conical extension *h* as also around the circumference of the said roof *i* and which is chiefly intended to protect the interior against entering rain, snow and sunrays.

I claim:

In a ventilator for buildings and vessels, in combination a pipe having inwardly bent indentations (*d*) at its upper end each indentation covered by a cap (*f*) of conical form, forming therewith air-channels open at top and bottom, a frusto-conical shield 55 surrounding said caps and forming therewith additional air-channels exterior to the caps, the said shield being extended above the top of the pipe, the upper end of the shield being flared; a double conically shaped roof *i* mounted spaced above the top of the pipe and a cylindrical shield surrounding the roof and the flared end of the conical shield.

TRAUGOTT KERNCHEN.
